UNITED STATES PATENT OFFICE.

EDWARD POSSON, OF CHICAGO, ILLINOIS.

HATCH-COVER AND VENTILATOR FOR REFRIGERATOR-CARS.

1,072,164.

Specification of Letters Patent.

Patented Sept. 2, 1913.

Application filed February 29, 1912. Serial No. 680,729.

To all whom it may concern:

Be it known that I, EDWARD POSSON, a citizen of the United States, residing at Chicago, in the county of Cook and State of Illinois, have invented certain new and useful Improvements in Hatch-Covers and Ventilators for Refrigerator-Cars, of which the following is a specification.

The principal object of my invention is to provide a new and improved cover for the hatchway of a refrigerator car.

Another object of my invention is to provide such a cover with means for ventilating the car.

Another object of my invention is to provide a hood over the hatchway of a refrigerator car with a plug for opening or closing the hatchway and improved means for ventilating when the plug is opened.

All these objects and others will be made clear in connection with the following specification and claims, taken with the accompanying drawings. In these drawings I have illustrated one specific embodiment of my invention and a modification thereof. I now proceed to describe these particular forms of the invention.

Figure 1 is a perspective view of the hood in closed position. Fig. 2 is a longitudinal vertical section. Fig. 3 is a top plan view partly broken away, and partly in section on the line 3—3 of Fig. 2. Fig. 4 is a horizontal fragmental section on the line 4—4 of Fig. 2. Fig. 5 is longitudinal vertical section of a modification.

Referring first to Figs. 1, 2, 3 and 4 the refrigerator car roof 15 has the usual hatchway 16 at the end over the ice box. This hatchway 16 has downwardly converging side walls 17 and may be closed by the plug 18 which has packing 19 around its sides. Over the hatchway 16 is a hood designated generally by the reference numeral 20. The frame composed of the angle irons 39 and 40 surrounds the upper edge 38 of the hatchway 16. At one side this frame carries the stationary members of the hinge 21, the movable members 45 being riveted to the outside of the sloping face 22 of the cover 20. Short alining shafts 24 are journaled in two opposite side walls of the hood 20. Within the hood these shafts 24 are rigidly connected to the ends of the arms 25 of the bail 26. The plug 18 has two iron straps 27 bolted thereto, but spaced from the plug so as to form slots 28 through which the

bail 26 passes. Outside of the casing 20 the lever or crank arm 29 is connected to one of the short shafts 24, and by this means the bail 26 may be rotated. At the side of the hood 20, away from the hinges 21, the top cover is bent upwardly, as designated by the reference numeral 30, and carries the handle 46. The side of the hood 20, away from the hinges 21, is composed of a sheet metal plate 31 below and woven wire netting 32 above. Inside of the hood 20 back of the netting 32 is a depending baffle 33. Below this baffle 33 the hood carries two deflectors 34 and 35 which catch any water that may run down from the baffle 33 or down the inside face of the wall 31, and direct such water upon the roof of the car. The hood 20 carries a staple 37 which may be engaged by a hasp 36 on the roof in order to fasten the hood down. The plug 18 carries eyes 42 which are loosely engaged by the studs 43 on the ends of the arms 41. At their other ends these arms are connected by hinged points 23 to the hood 22. The spaced loops 47 on the plug 18 over the arms 41 permit only slight angular movements of the plug 18 relatively to said arms 41. The hinge members 44 lie directly under the outside hinge members 45 and are riveted together with the sloping wall 22 of the hood between them. As shown in Fig. 2 the opening in the eye or lug 42 is slightly elongated, so that the stud 43 and said eye 42 can be relatively slightly displaced. As shown in Fig. 2, the plug 18 is closed. Without raising the hood 20 the plug 18 can be opened by throwing the lever 29 over about 180 degrees. The slots 28 under the straps 27 permit the bail 26 to slide therein. The dotted lines in Fig. 2 show the relation of the parts when the plug 18 is opened up. It will be seen that the bail 26 has a wedging action to close the plug; that is, in the full line positions of the parts in Fig. 2 a downward pressure on the lever 29 gives a powerful mechanical advantage to crowd the plug 18 down into the hatchway 16. On the other hand, when the plug is to be raised the arrangement of the parts gives a powerful mechanical advantage for this purpose to an upward pull on the lever 29. The plug 18, being carried on the ends of the arms 41, can move relatively thereto and so take an angular position accurately fitting into the hatchway. Also, the plug 18 can be displaced a little horizontally in any direction

by virtue of the pin and slot connections 42, 43. The wire netting 32 is of fine enough mesh so that it arrests most of the water in the air going through it. The water arrested on the netting 32 will run down the same and down the wall 31 partly on the inside and partly on the outside thereof. Any water that may chance to be carried under the hood 20 by air passing through the netting 32 will be caught on the baffle 33 and drip down from the lower edge thereof to the deflector 34.

Referring now to the modified embodiment of my invention shown in Fig. 5, the 15 plug and the mechanism for operating it are substantially the same as already described. The hood 20 is made so as to take the air in a reverse direction as compared with the hood shown in Figs. 1 to 4. The 20 sloping upper wall 22 of the hood 20 is continued as 22' and then bent down to form a baffle 33'. Between the portions 22 and 22' is placed the vertical perforated screen of wire mesh designated 32'. From 25 the upper edge of this screen 32' the curved sheet metal wall 30' extends and connects with the upper edge of the side wall 31. The handle 46' is attached to the top part of the hood 20. In this form of my invention the operation of the plug is the same as previously described. It will be seen that the hood is adapted to take in air in the reverse direction as compared with Figs. 1 to 4. The baffle 33' delivers its 30 water on the deflector 34. The curving wall 35 20 and the baffle 33' bound a conduit through which the air passes from the screen 32' under the lower edge of the baffle 33' and thence down into the hatchway 16. 40 It will be seen that I have provided a convenient ventilating closure for a refrigerator car hatchway, that is simple and inexpensive to construct, easily operated by persons of ordinary skill, and not liable to 45 get out of order.

I claim:

1. In a device of the class described, a car roof having a hatchway therein, a hood over said hatchway, said hood being hinged 50 at one side thereof, a plug for the hatchway under the hood, and a link pivoted at one end to the hood close to its hinge, and at the other end to the middle of the plug.
2. In a device of the class described, a car 55 roof having a hatchway therein, a hood over said hatchway and extending to one side thereof, a perforated screen across the extended side of the hood, and a baffle within the hood back of said perforated screen.
3. In a device of the class described, a car 60 roof having a hatchway therein, a hood over said hatchway and extending to one side thereof, a perforated screen across the extended side of the hood, a baffle within the 65 hood back of said perforated screen, and a

deflector below said baffle to catch water dripping therefrom and direct it aside from the hatchway.

4. In a device of the class described, a car roof having a hatchway therein, a hood over 70 said hatchway, said hood having a vertical wall at one side, the lower part of said wall being solid and the upper part perforated, and a baffle within the hood between said perforated portion of the side 75 wall and the hatchway.

5. In a device of the class described, a car roof having a downwardly converging hatchway therein, a hood over said hatchway, a plug within the hatchway, mechanism for raising or lowering said plug within the hood without displacing the hood, an operating handle for said mechanism outside the hood, and pivotal means connecting said plug to the roof adjacent to the hatchway, said means comprising a pin and slot connection so as to permit lateral adjustment of the plug to fit the hatchway.

6. In a device of the class described, a car roof having a hatchway therein, a hood over 90 said hatchway hinged at one side thereof, said hood extending beyond the hatchway on the side opposite the hinge, a perforated screen across the extended side of the hood, a baffle within the hood between the perforated screen and the hatchway, and a deflector below the baffle to catch water dripping therefrom and direct it from the hatchway.

7. In a device of the class described, a car 100 roof having a hatchway therein, a hood over said hatchway hinged at one side thereof, a plug for the hatchway under the hood, and two links hinged to the hood close to its hinge axis and attached at their extremities 105 to the middle of the plug.

8. In a device of the class described, a car roof having a hatchway therein, a hood over said hatchway hinged at one side thereof, a plug for the hatchway under the hood, and 110 two links hinged to the hood close to its hinge axis and attached at their extremities to the middle of the plug, the attachments of said links to said plug being loose to permit limited adjustment.

9. In a device of the class described, a car roof having a hatchway therein, a hood over said hatchway hinged at one side thereof, a plug for the hatchway under the hood, two arms hinged to the hood and attached at 120 their extremities to the middle of the plug, the attachments of said arms to said plug being loose to permit limited adjustment, and operating mechanism extending through the hood, whereby the plug may be raised 125 or lowered from the outside without raising the hood.

10. In a device of the class described, a car roof having a hatchway therein, a hood over 130 said hatchway, a perforated screen forming

a vertical portion of the wall of the hood, and a baffle interposed in the path of air currents between said screen and the hatchway.

11. In a device of the class described, a car roof having a hatchway therein, a hood over said hatchway, a perforated screen forming a vertical portion of the wall of the hood, a baffle interposed in the path of air currents between said screen and the hatchway, and

10 a deflector to catch water from said baffle and direct it aside from the hatchway.

12. In a device of the class described, a car roof having a hatchway therein, a hood over said hatchway, a perforated screen forming a vertical portion of the wall of the hood, and a baffle interposed in the path of air currents between said screen and the hatchway, said hood being extended to one side of the hatchway and said baffle having its lower

20 edge directed toward the extended side of the hood.

13. In a device of the class described, a car roof having a hatchway therein, a hood over said hatchway, a plug for the hatchway

25 hinged at one side under the said hood, said

hood having an opening directly above the said plug, said opening being adapted to admit air from the direction of the hinged side of the said plug, and a perforated screen across said opening, said hood having a 30 conduit extending from said opening around the edge of the plug away from the hinge when said plug is in open position.

14. In a device of the class described, a car roof having a hatchway therein, a hood over 35 said hatchway hinged at one side thereof, a plug for the hatchway under the hood, links pivoted to the hood close to its hinge axis and extending radially therefrom within the hood, the extremities of said links being 40 pivotally connected to the said plug near the middle thereof, and the said plug having loops loosely engaging the links.

In testimony whereof, I have subscribed my name.

EDWARD POSSON.
